LEONARD KAY WRIGHT, OF ASTORIA, LONG ISLAND CITY, NEW YORK

COMPRESSION REFRIGERATING APPARATUS

Application filed August 27, 1926. Serial No. 131,944.

The invention and improvements relate to compression refrigerating machines and apparatus, more particularly apparatus designed for household use, and the chief object 5 is to provide improved apparatus simple in construction and low in cost which may be operated with greater efficiency. To this and other ends the novel features are illustrated and described in the accompanying text and drawings in which:

Figure 1 is a diagrammatic illustration of a compression refrigerating system embodying my invention.

Figure 2 is a diagrammatic illustration of 15 a modified form of part of the apparatus shown in Figure 1 and,

Figures 3 and 4 respectively are diagrammatic illustrations of two modifications of 20 my improved evaporator unit.

Fig. 1 is a diagrammatical view of a compression refrigerating system, in which A is the compressor, B the condenser, these two aforementioned being interconnected by the discharge line H, C is the receiver, which 25 acts also as an oil separator, D is the liquid line which supplies the throttle or expansion valve E with liquid refrigerant, F being the evaporative section which is placed in the chamber to be cooled and G is the suction line which conducts the gasified refrigerant 30 to the pump or compressor. I is the oil line which supplies the pump with lubricant. In such systems where the lubricant is of greater density than the refrigerant, as for instance, ammonia and oil, ethyl chloride and 35 glycerine, the oil supply line I is so placed that it taps the lowest portion of the receiver and conveys nothing but oil to the compressor, while the liquid refrigerant line D is 40 placed with its open end at a higher elevation, so as to tap the refrigerant from which the oil has settled. Arrows denote the direction of flow through the various pipes or tubes.

Rotary compressors require a rather copious amount of lubrication and are usually connected to a vertical discharge line which connects to the top of the condenser. Due to the large amount of lubricant handled the 45 vertical discharge line tends to clog and pre-

vent an even flow of compressed gas to the condenser, while the lubricant fed into the top of the condenser forms in a film around the condensing surfaces and greatly retards heat transfer.

In Fig. 1 is shown my improvement, which 55 consists of placing the discharge line about two thirds below the top of the condenser. By this method most or all of the vertical rise in the discharge line is eliminated and 60 the discharged gas and oil, in leaving the discharge pipe H, impinge upon the vertical condenser tube or tubes, which allows the entrained oil to fall to the bottom; the warm oil-free gas rising to the upper portion of 65 the condenser, which, not having oil films to retard heat transfer, condenses the gas with 70 greater efficiency. The liquefied refrigerant trickles down the condenser tubes and collects in the receiver C. It is obvious that 75 two thirds of the condensing surface is thus kept in an oil free condition and through the elimination of these oil films enables the condenser to function with greater efficiency, which permits a reduction in size. This 80 maintenance of two thirds or more of the condenser surface in an oil free condition, conducive to greater heat transfer and a reduction in size, is one of the objects of my invention.

In Fig. 2 is shown another method of construction in which B is the condenser, H being the discharge line which is connected to the condenser tube J, C is the receiver, D the liquid line and I the oil supply line. A household refrigerating machine of simplest design would use the first method of construction, that is the condenser would act also as a reservoir or receiver, while the second construction, which uses a separate condenser 85 and a separate receiver, would be used on larger and more complicated machines.

Another object of my invention is to improve the operating efficiency of evaporators. All evaporators in such systems where the 90 lubricant is of greater density than the refrigerant suffer through oil accumulation, which affects the efficiency to an extent depending upon the amount of the accumulation; the accumulation displacing liquid refrigerant.

rant, while the oil film is spreading itself over the surface of the evaporator impairs heat exchange. In some cases evaporators trap the total charge of oil that was placed in the machine, and may end in the destruction of the compressor, for without lubricant the moving portions score and grind themselves beyond repair.

In Fig. 3 is shown my improvement applied to an evaporator, the purpose of which is to remove all oil or lubricant accumulations so that at the beginning of each cooling period the evaporator will be in an oil free condition. The liquid line D which supplies the refrigerant to the throttle or expansion valve E may be placed so as to feed the evaporator section F from the top, bottom or at any convenient point, but the gas line L, which is connected to the suction line G, must be connected on, at or near the top of the evaporator section F, so that when the evaporator section is operating in its heat removing capacity nothing but gaseous refrigerant will be drawn back to the compressor. A siphon tube K is placed in the evaporator section, one end in close proximity with the lowest portion of the evaporator section, the other end of the siphon tube being connected to the suction line G.

30. In operation the following occurs:

When the compressor has been operating a sufficient length of time so that the required coolness in the refrigerated space is attained the current is shut off and the compressor stopped. The condenser and receiver, being subjected to the warmth of the atmosphere, are under a higher pressure than the evaporator and continue to force liquid refrigerant through the liquid supply line D, through the expansion valve E, into the evaporator chamber F. The temperature and pressure difference between the high side and the low side causes the evaporator to fill with liquid refrigerant. As soon as the tube K is immersed and becomes filled it will begin to function as a siphon, and begin to unload the evaporator of any oil which had been trapped from the previous refrigerating operation; the oil and liquid refrigerant passing through the siphon tube K and draining into the suction line G. When the suction line has filled with oil or liquid refrigerant the evaporator section will continue to fill until very little gas space remains. When the machine is again called upon to perform its refrigerating duty and a suction is produced in the return line G the siphon tube K will further unload the evaporator section of lubricant and liquid refrigerant, which collected in the evaporator. The evaporator F being entirely emptied of all lubricant is in the best heat exchanging condition, so that the liquid refrigerant entering from the expansion valve E will evaporate or boil in direct contact with the evap-

orator section, unhindered by oil films or through displacement by their accumulation.

The loop in K must be placed so as to be just beneath the gas return opening L, for it is obvious that if the loop was located above the gas line L it would never function as a siphon, due to the fact that it would never become filled with liquid. This gas line is preferably placed at the highest point of the evaporator, that is on, at or near the top, so that the loop K can be inserted in the evaporator with the top of the loop touching the inner side of the top of the evaporator. By doing so the liquid level is maintained at maximum height, leaving very little gas space. It is well known in the art that an evaporator will function best when the inner surfaces are wet with liquid refrigerant, as the gaseous refrigerant performs very little refrigerating duty, and therefore the gas space should be as limited as possible.

Fig. 4 shows an evaporator equipped with the oil removing siphon tube which utilizes a cup or depression to collect the lubricant. The siphon tube is inserted so that one end is immersed in the cup X, the other end of the siphon tube being connected as previously stated, to the suction line G.

While I have illustrated in the foregoing specification and the accompanying drawings certain specific embodiments of my invention, I wish it to be clearly understood that such illustrations are not to be taken as limitations of the scope of my invention, but are merely for the purpose of disclosing a single embodiment thereof. I do not wish to be limited in the scope or practices of this invention except by the terms of the appended claims.

Having described my invention and improvements what I claim as new is:

1. In a refrigerating apparatus, an evaporator equipped with a supply line, a suction line, and a siphoning tube so arranged that in normal operation a portion of its length is above the surface of the liquid refrigerant; one end of the siphoning tube being in close proximity with the lowest portion of the inside of the evaporator the other end of said tube being connected to said suction line. 110

2. In a refrigerating apparatus, an evaporator, a conduit connected therewith adjacent the upper portion thereof for supplying a refrigerant thereto, an outlet conduit connected with said evaporator adjacent its upper portion and means mounted in said evaporator for draining substantially all of the liquid therefrom automatically when the liquid reaches a predetermined level. 120

3. In a refrigerating apparatus, an evaporator, a conduit connected therewith adjacent the upper portion thereof, for supplying a refrigerant thereto, an outlet conduit connected with said evaporator adjacent its upper portion and means mounted in said 130

evaporator for draining liquid therefrom when the liquid reaches a predetermined level, said means comprising a siphon, one end of which is arranged adjacent the lower portion of said evaporator and the other end of which extends through said evaporator to a point of discharge.

4. In a refrigerating apparatus, an evaporator, a conduit connected therewith adjacent the upper portion thereof, for supplying a refrigerant thereto, an outlet conduit connected with said evaporator adjacent its upper portion and means mounted in said evaporator for draining liquid therefrom when the liquid reaches a predetermined level, said means comprising a siphon, one end of which is arranged adjacent the lower portion of said evaporator and the other end of which communicates with said outlet conduit.

5. A refrigerating apparatus comprising a source of liquid refrigerant and an evaporator, said evaporator having a refrigerant inlet and a refrigerant outlet and a siphon mounted in said evaporator adapted to discharge oil introduced therein.

6. In a refrigerating apparatus an evaporator, a conduit connected therewith adjacent the upper portion thereof, for supplying a refrigerant thereto, an outlet conduit connected with said evaporator adjacent its upper portion and means mounted in said evaporator for draining liquid therefrom when the liquid reaches a predetermined level, a cup like depression in the lower portion of said evaporator, said means comprising a siphon, one end of which is arranged within said depression and the other end of which extends through said evaporator.

40 7. In a refrigerating apparatus, an evaporator, a conduit connected therewith adjacent the upper portion thereof, for supplying a refrigerant thereto, an outlet conduit connected with said evaporator adjacent its upper portion and means mounted in said evaporator for draining liquid therefrom when the liquid reaches a predetermined level, a cup like depression in the lower portion of said evaporator, said means comprising a siphon, one end of which is arranged within said depression and the other end of which communicates with said outlet conduit.

45 In testimony that I claim the foregoing as my own, I have hereto affixed my signature.

50 LEONARD KAY WRIGHT.
